CLAIM

The ornamental design for a brassiere, as shown and described.

DESCRIPTION

FIG. 1 is a front isometric view showing an embodiment of my design for a brassiere of the present invention, in a closed state.

FIG. 2 is a front elevation view thereof.

FIG. 3 is a rear elevation view thereof.

FIG. 4 is a right-side elevation view thereof.

FIG. 5 is a left-side elevation view thereof.

FIG. 6 is a top elevation view thereof.

FIG. 7 is a bottom elevation view thereof; and,

FIG. 8 is a front elevation view, with the right side of the brassiere in an open state or position.

The broken lines in the drawings depict stitching and form part of the claimed design.
